WEIGHTED FISH HOOK

William J. Jeff, P.O. Box 3654,
Birmingham, Ala. 35211

Filed Mar. 27, 1968, Ser. No. 11,152

Term of patent 14 years

Int. Cl. D22—08

U.S. Cl. D22—30

Fig. 1

Fig. 2

Fig. 3

FIG. 1 is a side elevational view of my weighted fish hook;

FIG. 2 is a bottom plan view thereof; and

FIG. 3 is a side elevational view of a modified form of my weighted fish hook in which the weedless element is omitted.

I claim:

The ornamental design for a weighted fish hook, as shown and described.
